CHARLES KINKEL, OF NEW YORK, N. Y., ASSIGNOR TO ALEXANDER WEHLE, OF SAME PLACE.

Letters Patent No. 63,059, dated March 19, 1867.

IMPROVEMENT IN PLOUGHS.

The Schedule referred to in these Letters Patent and making part of the same.

TO WHOM IT MAY CONCERN:

Be it known that I, CHARLES KINKEL, of the city, county, and State of New York, have invented a new and improved Plough; and I hereby declare the following to be a full, clear, and exact description thereof, reference being had to the annexed drawings, making a part of this specification, in which—

Figure 1 represents a horizontal view of the plough.

Figure 2, a front view of the same.

Figure 3, a side view of the same.

Figure 4, a longitudinal section through the line C d of fig. 2.

Figure 5 is a cross-section through the line a b of fig. 3.

Figure 6 is a perspective view of the application of my improvement to existing ploughs.

The same letters of reference mark the same parts in all these figures.

The nature of my invention consists in the construction of a self-holding plough, the course of which during the ploughing is regulated by means of a universal joint connected with the plough-frame and plough-beam, substantially as hereinafter described.

To enable others skilled in the art to make and use my invention, I will proceed to describe its construction and operation.

In the annexed drawing, A represents the ploughshare. B the plough-beam. C the plough-frame. D the axle of the wheels connected with the frame. E¹ E² the wheels. F the screw-tree. G the universal joint. H the cart-shaft. I the chain connecting it with the plough-beam. K the plough-beam handle. L the plough-share base. The frame C consists of cast iron, to which the screw-tree F is fastened. Said screw-tree is connected with the plough-beam by means of the universal-joint piece, one end of which is a mother-screw holding the screw-tree F, and the other end of which slides in the double slot n of the plough-beam, whereby the plough-beam may be turned horizontally or vertically, as may be desired, without admitting of any vacillating motion in its vertical position. The lower end of the frame contains several openings m m m to receive the lower end of the screw-tree, the upper end of which is adjustable by means of the slot p in which a connecting piece is made to slide, and when in the position desired it may be fixed therein by the screw-handle r. The cart-shaft H is connected on the lower side of the frame with semicircular extension piece h of the frame, containing cuts i i i, in which the shaft H may be fitted, and in either one of which it may be fixed by means of the screw-handle g. By means of the screw-tree and the shaft the width of the furrow may be regulated at pleasure. The axle D is connected with the frame C in such a manner that at s, near the small wheel, it is fastened to the frame by means of a screw which permits a slight turning, while near the other end, at t, there are a few holes in the frame into either of which it may be fastened by a pin, so as to permit a slight raising or lowering of the big wheel, whereby the depth of the furrow may be regulated at pleasure in connection with putting the universal joint higher or lower on the screw-tree. The handle K at the end of the plough-beam is placed there only for the purpose of lifting the ploughshare out of the furrow when required, and not for the purpose of leading the plough. The back part of the ploughshare base L is provided with a cast-iron piece, L, in the form shown in figs. 3 and 5, which is fastened to the said base by screws, and which, when rendered useless by being rubbed off, may be removed and another piece screwed on in its stead; this being a part of the plough which is most liable to be ruined by the constant friction between it and the firm part of the furrow.

The advantage of this plough over all others in use, is that it is rendered self-holding and self-regulating, dispensing with the leading of the ploughshare or plough-handle without being more complicated in its construction than the usual plough; and the plough-frame C may be applied to all kinds of existing ploughs, whereby they may be rendered more useful and easier of management.

In order to apply my said improvement to existing ploughs, I use the construction represented in fig. 6 of the drawings.

B (in said figure) represents the plough-beams of a usual plough. R, a cast-iron shoe which may be fastened thereto by the screw S. Q is a cast-iron side piece which prevents the turning of the ploughshare toward the inside of the furrow. The said side piece is turnable vertically on the screw-bolt T, which also serves as pivot

for the universal joint G, in which the screw-tree F is held. P represents a longitudinal screw-bolt on which the shoe R turns, and also holds the side piece Q. In this manner a horizontal and vertical rotation of the plough may be attained without requiring any alteration in a plough-beam of the usual construction, and thus all ploughs may be conveniently provided with my said improvement. The shoe R may be shoved further or nearer to the end of the plough-beam by the use of the screw S.

What I claim as new, and desire to secure by Letters Patent of the United States, is—

1. The general construction of the plough, consisting of the plough-frame C, in connection with the axle D, the plough-beam B, screw-tree F, and shaft H, substantially as described.
2. The plough-frame C, in combination with the screw-tree F, and universal joint G, substantially as set forth.
3. The universal joint G, applied to the plough-beam B, and screw-tree F, substantially as described.
4. The movable axle D, in combination with the plough-frame C; substantially as described.
5. The application of my improvement to ploughs of the usual construction by means of the cast-iron shoe R, substantially as described.

CHAS. KINKEL.
